REMOVABLE FORM FOR CONCRETE WALL
CONSTRUCTION

Jabez Taylor Mitchell, Claremore, Okla.

Application September 24, 1943, Serial No. 503,677

7 Claims. (Cl. 25—131)

This invention relates to a wooden, metal or earthen form which may be removed after the cement or concrete mass has hardened leaving a wall which is readily adaptable to many methods of finishing on both the exterior and interior sides. This type of form, when removed from the wall will leave a wall of concrete or cement with, when viewed from the side, a honey-comb appearance. This wall might be designated as an inner-wall since in building construction it is anticipated that both exterior and interior sides of the wall would be finished in a manner suitable to the builder. However the wall without finishing would be suitable to such uses as exterior wall or front of a porch, side wall for cribs, or for fences or a variety of building needs.

A special object of the invention is to so design the forms that when they are removed a relatively light and strong wall of concrete and reinforcing material will be left. Many pockets will be left in the wall, open at the tip to a similar pocket on the other side of the wall and suitable for inner ventilation of the wall or the insertion of insulating materials. Such a wall would also afford the opportunity for the attaching of an exterior or interior wall by a variety of methods using the original concrete wall as a base.

Another special object of the invention is to give builders a greater flexibility in wall design. These forms can be made so that a wall with any practicable curvature can be made and buildings can be constructed without the necessity of having a corner. This would free house planners from the more conventional design in which straight side walls with right-angle corners are largely utilized.

Another special object of the invention is to give a wider variety in window and door design but at the same time make easy a solid and airtight construction where windows and doors, or window frames and door frames are attached to the main wall of the building.

Another special object of the invention is to make easier solid concrete wall construction under certain circumstances. Such an inner-wall could be built and then it used as a rigid inner framework to which outside, conventional form could be attached for the pouring of the concrete.

Another special invention is to furnish a building with a strong inner wall, not subject to decay and having the mechanical strength to resist storms.

According to the invention these forms are made in sub-units. Two of the sub-units, prop-

erly arranged with regard to each other and held together by a through-bolt or some other suitable method may be said to make up a unit. A plurality of these units are then placed beside and upon each other, their length transversely to the length of the wall. Bracing and reinforcing wires may be used to tie the forms together and give rigidity to the assembled forms. The interior open spaces or recesses formed being filled with concrete and reinforcing materials and the forms left on until the concrete hardens. The forms may then be removed after removing the through-bolts and the wall will then be left as described above.

Figure 1 is a cross section of wall showing the forms before they are removed. The wall itself is represented as being integral with the foundation.

Figure 2 represents two half-units assembled 20 on a through bolt.

Figure 3 is an end view of one form of the base-block.

Figure 4 is a view from the inside of a half unit in which the central member is represented 25 as a truncated pyramid.

Figure 5 is a cross section of a one-half unit which might be considered to be metal and the central member cast integral with the base block.

Figure 6 represents base blocks as converging 30 toward a center of curvature of the wall which is under construction.

In the drawing:

Figure 1 is the vertical cross section of the removable forms and wall while the forms are 35 still attached to the wall. The forms are represented as being made of wood. The reference numeral 1 indicates what might be called the base-block. The numeral 2 indicates the extension of the base-block which may be integral with the base-block or may be a separate member but secured when assembled, to the base block by the through-bolt. This extension will be referred to as the central member or neck. The small end of the neck will be referred to as the top 40 of the one-half-unit and the end of the base-block showing outside of forms and in contact with the head of, or nut of, the through-bolt as the bottom of the one-half-unit. The numeral 3 indicates an end of the through-bolt. The numeral 4 indicates a cross section of some reinforcing material such as wire or steel rod. This wire may be found in various positions in the cross section of the concrete material since it could be used vertically, horizontally or diagonally to secure the forms together while the con-

crete is being poured or worked into the recesses between the one-half-units of the forms. The numeral 5 indicates the concrete or similar material in cross section. The numeral 6 represents the position of a bolt which might be added to the concrete to secure the superstructure. In a side wall such a bolt might be used to secure window or door structures or attach wall to a corner or an adjacent wall. The numeral 7 indicates a concrete foundation which due to the nature of the material would be firmly bound to the inner-wall above. The numeral 8 indicates earthen materials surrounding the foundation.

In Figure 2 such a removable form is represented completely assembled. The numeral 1 indicates the base-block. The numeral 2 the neck and the numeral 3 the through-bolt. The left one-half unit is numbered but the right one-half unit is similar except that its position is reversed in order that the top part of the necks may be in contact with each other and held so due to the action of the through-bolt.

Figure 3 represents the outside end of a base-block. The numeral 1 indicates the end or bottom of base-block and the numeral 3 the end of the through-bolt. The end or bottom of base-block is represented as being square and this form should lend itself to more convenient use in building although the base-blocks may be rectangular, hexagonal, or any other polygonal shape.

Figure 4 is a top view of a one-half unit in which the neck, which may be integral with the base-block or a separate piece, is represented as a truncated pyramid of four sides. This form of neck may be used or it may be a truncated cone or part of a sphere or a section of an ellipsoid the essential feature being that it is removable after the concrete has set.

Figure 5 is a cross section of a modified embodiment of the invention. The base-block 2 is hollow and the neck is integral with the base-block and hollow. This would be a convenient form in case the half-unit was to be cast from metal.

Figure 6 represents the building unit as in Figure 2 except that two of the opposite sides of base-block are not parallel with each other but sloped toward a line which would be the center of curvature of the wall under construction. If the four

sides of the form sloped or converged toward a point instead of a line it would give the wall under construction a dome shape.

The material from which the building forms 5 are made could with certain advantages be made of wood. These by being pre-soaked with water would not expand when in contact with the wet concrete. The wet wood would be a source of water for the curing concrete. Upon drying the 10 wooden forms would shrink sufficiently to make them removable. A metal base-block would have the advantage of weight while the forms were being laid. A combination of metal base-block and wooden neck or wooden base-block and metal 15 neck would each have its advantages. The metal neck could be handled more roughly while removing from wall without damage to its form.

1. claim:

1. A removable form for concrete wall construction consisting of two base-blocks and two central members all of which are drilled parallel to the longitudinal axis of the form for the reception of a through-bolt, the central members having larger ends which rest against the base-blocks 20 and smaller ends which rest against each other in the central part of the wall under construction, the entire unit consisting of two base-blocks assembled with the two central members between them upon a suitable through-bolt and placed 25 transversely to the wall under construction.

2. A removable form as set forth in claim 1 all parts being of metal.

3. A removable form as set forth in claim 1 the base-blocks being of metal and the central members being of wood.

4. A removable form as set forth in claim 1 the base-blocks being of wood and the central members being of metal.

5. A removable form as set forth in claim 1 except that the central members are integral with their respective bases.

6. A removable form as set forth in claim 1 except that the central members are integral with their respective base-blocks, the base-blocks 45 and central members being of metal.

7. A removable form as set forth in claim 1, wherein the longitudinal sides of the base-blocks converge toward the center of the form.
